UNITED STATES PATENT OFFICE.

DAVID R. SMITH, OF COHOES, NEW YORK, ASSIGNOR TO JOHN McCREARY,
EDWARD McCREARY, AND ALVA C. SMITH, ALL OF SAME PLACE.

COMBINATION CIPHER-MACHINE.

SPECIFICATION forming part of Letters Patent No. 312,665, dated February 24, 1885.

Application filed September 12, 1884. (No model.)

To all whom it may concern:

Be it known that I, DAVID R. SMITH, of Cohoes, county of Albany, and State of New York, have invented a new and useful Improvement 5 in Combination Cipher-Machines, of which the following is a full, clear, and exact description, reference being had to the accompanying drawings, making part of this specification.

This invention relates to that class of combination cipher-machines in which series of letters, figures, words, signs, or symbols in regular order, and having their usual, customary, and generally understood significance, are brought into juxtaposition with series of 15 the same or other signs, symbols, or characters capriciously or irregularly arranged in such manner that the latter may be conveniently used as secret characters or ciphers to represent the former in secret correspondence, 20 or for other similar purposes.

The object of the invention is to provide an improved combination cipher-machine for general use which shall be susceptible of a practically unlimited number of combinations, 25 more so than the combination-locks used to secure the doors of safes and bank-vaults, whereby, no matter how many persons may use this invention, each pair of correspondents may by its aid be provided with a cipher-code 30 different from every other such code, and practically impossible to decipher by any one not possessing the key.

For the purposes of this description of my invention I will designate the letters, signs, 35 words, phrases, characters, symbols, &c., when employed with their usual or customary meaning or significance, as conventional letters, signs, &c., and the same or other letters, signs, symbols, characters, &c., when employed to 40 represent the former, or as representing the former, as cipher letters, words, symbols, &c.—that is to say, when given an arbitrary or unusual meaning or significance I will designate them as cipher letters, words, figures, 45 symbols, &c., or simply as cipher.

My invention consists of a machine in which conventional letters, as the alphabet, or conventional numerals, as 1 2 3 4 5 6 7 8 9 0, or other conventional characters, signs, words, 50 symbols, &c., are arranged in their usual or regular order, in a direct line, or in direct or

straight lines, across the faces of a series of coaxial cipher wheels or disks, the said cipher wheels or disks carrying the same or other letters, figures, signs, words, characters, &c., 55 to be employed as ciphers or characters to be used in secret correspondence, and to represent the conventional signs, characters, or symbols, &c., with which they are, by the concerted movement of the parts of the machine, brought into juxtaposition.

While for especial purposes any suitable signs, letters, characters, words, symbols, &c., may be employed in my invention, the twenty-six letters of our alphabet and the numerals 1 65 2 3 4 5 6 7 8 9 0 will suffice for general purposes.

In the accompanying drawings, Figure 1 is a front elevation of a machine embodying my invention. Fig. 2 is a transverse section 70 through the center of the same. Figs. 3 and 4 illustrate certain modified details of Figs. 1 and 2. Fig. 5 is the letter cup or box, and Fig. 6 represents a front and an edge view of a letter-block. Fig. 7 is a plan, Fig. 8 1 a elevation, and Fig. 9 details, of a modified form of the machine shown in Figs. 1 and 2.

In all the figures A is the bed-plate, B the cipher-wheel shaft or axle. $a^1 a^2 a^3 a^4$, &c., are the cipher-wheels fitting loosely on that axle, and having notches $b b$, which engage the hooked ends of stop springs or pawls $c c$. C 85 C are thumb-nuts, which, working in screw-threads cut in the cipher-wheel axle B, clamp the cipher-wheels together, when required, so that all the said wheels a will turn with the axle B, or when the thumb-nuts are turned in the opposite direction will loosen the cipher-wheels and allow each and all of them to be turned freely about the axle. In Figs. 1 90 and 2 the axle B is horizontal and supported by uprights $d d$ in bearings $e e$. In Figs. 7, 8, and 9 the axle B is vertical, and is firmly secured to the bed-plate at or near the center of that plate.

In Fig. 1, E is a hand-wheel for turning the axle, and F a friction-wheel upon which the adjustable friction-brake G bears, the pressure of said brake being regulated by the adjusting-screw H as required. The stop springs 100 or pawls $c c$ project from a bar, f . In Figs. 1 and 2, the bar f is pivoted to uprights $g g$, and

is provided with an adjusting-arm, *h*. *i* and *j* are adjusting-screws, the former working against and the latter screwing into the bed-plate. By manipulating screws *i* and *j* it is evident that the tension of springs *c c* can be readily regulated.

In Fig. 7 no means of adjusting or changing the tension or pressure of springs *c c* are shown, as any suitable means may be employed for that purpose.

In Figs. 1 and 2 the broadened ends of the springs *c* are utilized to carry the conventional signs or characters, which in this case are the alphabet and numerals, as shown, in a direct line across the faces of the disks *a' a² a³ a⁴*, &c.; but the spring-pawls *c c* may be placed in a different position, or may be suitably modified in form, and a straight-edge or blade, *I*, be employed to carry the conventional characters, &c.

The blade *I* in Fig. 3 is provided with lugs or projections *l*, by which it may be secured to the bed-plate *A*. In Figs. 7 and 8 the blade or straight-edge *I* is divided in two parts, *I' I'*, to avoid the employment of other ten wheels or disks *a*, to correspond to the numerals. The same economy of wheels or disks *a* may be effected, if desirable, in Figs. 1 and 2, by the use of an independent straight-edge, *I²*, for the numerals—that is, by dividing up the straight-edge *I* in that figure and using twenty-six, instead of thirty-six, wheels or disks *a*. In Figs. 7 and 8 the blade *I* is carried loosely between the thumb-nut *C* and a washer, *m*, as is clearly shown in Figs. 8 and 9, and at its outer extremity the blade *I* bends around the outer edge of a steady-disk, *J*, and carries a thumb-screw, *K*, by which it may be tightened and held stationary, or loosened to swing around the faces of the disks or wheels *a a*, from one to another of the radially-disposed lines of cipher letters or characters on the disks or wheels *a*. Upon the faces of all the outer edges of the wheels or disks *a*, as in Fig. 7, the cipher letters, signs, symbols, or characters, &c., are arranged.

In the examples shown in the drawings, and for general use, I employ as signs, characters, symbols, &c., the twenty-six letters of our alphabet only; but any suitable characters or symbols, words or signs may be employed for general or especial cases or purposes.

In the drawings only a part of the letters are shown. All the wheels or disks *a* in Fig. 1 are exactly alike, and each has a full alphabet on its face, all the letters of which are arranged in regular order and evenly spaced from *a* to *z*, the letters of the first twenty-six disks corresponding as ciphers to the letters of the alphabet, as conventionally employed, and shown in the direct or straight line across the faces of the disks *a*, and the letters on the other ten disks corresponding as ciphers to the numerals 1 2 3 4 5 6 7 8 9 0 in a similar manner.

In Fig. 7 the wheels or disks *a*—only twenty-

six in number—are lettered in similar order; but to reduce the number of wheels from thirty-six to twenty-six the letters brought into juxtaposition with the conventional numerals 1 2 3 4 5 6 7 8 9 0 on the blade or straight-edge *I²* are used as cipher-characters representing these numerals.

The letter-blocks and letter-cup shown in Figs. 5 and 6 are convenient for the purpose of selecting series of letters by chance when using my invention. The letter-blocks are any small disks or pieces of convenient size and form upon which the letters of the alphabet appear.

I will describe a simple manner of using my invention. Let us suppose that a merchant, *X*, of a certain city, having the machine as shown in Fig. 1, wishes to carry on a secret correspondence with another merchant, *Y*, who resides in some other city, and who also is provided with an exactly similar machine. The first thing required is that *X* and *Y* agree upon a cipher-alphabet, which shall be a key with which to set the machine. This can be done by chance very conveniently with the aid of the letter-cup and letter-blocks shown in Figs. 5 and 6. They may shake the twenty-six letter-blocks in the letter-cup and throw them out on the table, as shown in Fig. 5, then select the letters by chance, or "as they come," thus forming a key-cipher alphabet. Then return the letter-blocks to the letter-cup and shake the latter again and select ten more letters to serve as cipher-numerals. Let us suppose that the cipher letters and numerals selected by *X* and *Y* are *l v f p g h m r s w u t j k n b z o q d x a i c e y* for the twenty-six letters, and *o g m d l y c k f r* for the ten numerals. Let it be agreed between *X* and *Y* that the cipher-alphabet shall be changed for every word written in any secret communication between them. Then, to use the machine to write or to read the written cipher the machine must be set, as shown in Fig. 1, with the key-cipher alphabet and numerals forming a straight line in juxtaposition with the conventional alphabet and numerals, as shown in that figure.

To write, as by agreement, between *X* and *Y*, the first word would be written with the key-cipher alphabet shown in Fig. 1, the wheels having been previously clamped firmly together between washers *p*, by screwing up the thumb-nuts *C C* after setting the disks, as shown. To write the second word, *X* or *Y* would move all the disks together one letter or more, according to previous agreement, or until the spring-pawls *c c* pass from one line of notches into the next succeeding line or other line, as agreed, and so on for each succeeding word, turning the clamped disks around one notch, or more, as before, and using for each word a new cipher-alphabet thus brought into juxtaposition with the parallel straight line of conventional letters. The modification shown in Fig. 7 is used in a similar manner, except that the arm or straight-

edge I^2 does not require any key, it being governed by I' , and therefore the key-alphabet of such an instrument would consist of twenty-six letters only.

5 To use this invention for carrying on secret correspondence between parties at a distance, it is necessary that both parties have machines exactly alike, in practical detail, that the alphabetical key or some other key be agreed 10 upon to set the instruments alike and to govern the changes to be made when using the machines, either in writing or deciphering a secret communication; but it is evident that the number of combinations and changes possible is limited only by the permutations of 15 which the alphabet employed is susceptible; and having given one of the most simple ways of using this invention it is evident that every one using it can select his own methods in 20 the way of deciding on an alphabet, or selecting a key, or in changing the cipher or the significance of the cipher used.

By preparing a code in which a few letters represent many words and using the conventional letters to represent such words and the cipher-letters to represent the conventional letters a great many words may be communicated in perfect secrecy with a very few cipher-letters. For example, let a key-book be prepared in which write one thousand phrases numbered from 1 to 1,000. Then it is evident that any one of these phrases may be communicated with from one to four cipher-letters representing the number of the phrase.

35 In manufacturing my cipher-machine for sale for general use the thirty-six-disk machine should be provided with an extra blade or straight-edge, I^2 , so arranged as to correspond in position with the blade I' on twenty-six-disk machines, so that not only all twenty-six-disk machines will correspond with each other, but the first twenty-six disks of the thirty-six-disk machines having the blades I' and I^2 , or the equivalents of such blades, will 40 45 virtually constitute a twenty-six-wheel machine.

To distinguish between the cipher-letters representing conventional letters and those representing conventional numerals, any convenient sign agreed upon may be employed, such as simply underlining the numerals.

Having now described my invention, I claim as new—

1. A combination cipher-machine having a series of adjustable coaxial disks or wheels, a , 55 and supports or edges carrying or holding a line of letters, figures, characters, or symbols crossing the faces of said disks or wheels, substantially as described.

2. A combination cipher-machine having a 60 series of adjustable coaxial disks or wheels, a , provided with suitable letters, characters, figures, or symbols on their faces, or near their periphery, and a line of suitable characters, letters, figures, or symbols arranged across the 65 faces of said disks or wheels on suitable supports or edges, substantially as described.

3. In a combination cipher-machine, a series of adjustable coaxial disks or wheels, a , 70 carrying suitable letters, figures, characters, or symbols, in combination with a suitable nut or nuts, C , on the threaded axle of said disks or wheels, for clamping the latter together for simultaneous adjustment, substantially as described.

4. In a combination cipher-machine, a series of notched and adjustable coaxial disks or wheels, a , carrying suitable letters, figures, characters, or symbols, in combination with a suitable nut or nuts for clamping said disks 80 or wheels together on their axle for simultaneous adjustment, and a suitable yielding retaining pawl or pawls, c , engaging said disks or wheels and holding them at the desired adjustment, substantially as described. 85

5. In a combination cipher-machine, the combination of a series of adjustable coaxial disks or wheels for carrying the letters, figures, characters, or symbols to be used for the ciphers, a support or supports for conventional letters, figures, characters, or symbols arranged in a line or lines across the faces of said disks or wheels, a nut or nuts for clamping said disks or wheels together on a common axle, and a suitable pawl or pawls for holding 90 95 said disks or wheels at the desired adjustment, substantially as described.

In testimony whereof I have hereunto set my hand this 10th day of September, A. D. 1884.

DAVID R. SMITH.
